CLOTHES HANGER

William M. Gross, Wyndmoor, Pa., assignor to Nannette Manufacturing Company, Inc., Philadelphia, Pa., a corporation of Pennsylvania

Filed Feb. 11, 1965, Ser. No. 83,779

Term of patent 14 years

(Cl. D80—8)

FIG. 3.

FIG. 1 is a front elevational view of a clothes hanger embodying my design;

FIG. 2 is a side elevational view thereof;

FIG. 3 is a top plan view thereof;

FIG. 4 is a bottom plan view thereof;

FIG. 5 is an enlarged cross-sectional view along the line V—V of FIG. 1; and

FIG. 6 is an enlarged cross-sectional view along the line VI—VI of FIG. 1.

I claim:

The ornamental design for a clothes hanger, substantially as shown.
